UNITED STATES PATENT OFFICE.

CARL G. HARSTROM, OF PEEKSKILL, NEW YORK.

COLLAR-BUTTON.

SPECIFICATION forming part of Letters Patent No. 333,752, dated January 5, 1886.

Application filed May 28, 1885. Serial No. 166,922. (No model.)

To all whom it may concern:

Be it known that I, CARL G. HARSTROM, a citizen of the United States, residing at Peekskill, in the county of Westchester and State of New York, have invented certain Improvements in Collar-Buttons, of which the following is a specification.

My invention relates to collar-buttons that will adjust themselves to varying lengths and unequal strains upon collars that are buttoned to the shirt, and may be called "elastic collar-buttons."

Its object is to obviate some of the annoyances to which collar-wearers are subjected, a few of which I will enumerate. Often the back and front collar-buttons or button-holes, if removable buttons are used, do not equally divide the neckband of a shirt, so that when a collar is in place the band will wrinkle and chafe the neck.

Collars are not always made accurately as to length between the extreme button-holes, or, even when so made, are not always adapted to the lengths of collar-bands on shirts, and the result is a wrinkling of the band, squeezing and discomfort to the neck generally. Emergencies occur sometimes when a collar of just the right length cannot be obtained, and at such times the fortunate possessor of one of my elastic buttons may use a half-inch shorter collar than his usual size by cutting a small slit in the very extreme ends of the band just to admit the small buttons of my device. I have known a paper collar to be worn in this way for several days with button-holes that would hardly bear passing over a common button.

The means by which these objects are attained are set forth in the accompanying drawings, in which similar letters refer to similar parts throughout the various views.

Figure 1 is a front view of my device. Fig. 2 is a back view. Fig. 3 is a top view, and Fig. 4 is an edge view. Figs. 5 and 6 illustrate details in construction.

a represents the foundation-plate of my button, and is provided with slots *b*. To the center of this plate I fasten the button *c*, which is to be inserted in the manner of an ordinary collar-button in a shirt-band. Projection or flange *e* is a part of plate *a*, is

notched in the corners, and is bent forward, constituting a hook, to which a necktie elastic or fastening may be attached, as upon a common button.

The small collar-buttons *i* are shown in detail in Fig. 5. The end of the shank *h* is reduced in diameter, and is riveted firmly in arm *l*, as shown at *k*. This forms a shoulder, *j*, which is adapted to move freely in the slot *b* in *a*.

The parts in Fig. 5 are exaggerated in size for clear illustration. Arm *l*, there shown in section, it will be seen, is stamped into form from sheet metal.

The cup end *b'* is calculated to inclose a spring (shown, also exaggerated in size, in Fig. 6.) When the two arms *ll* are brought together and are riveted through their center, they present the appearance shown in Figs. 70 1, 2, and 4.

The spring A, Fig. 6, has its two ends bent at right angles in opposite directions, as seen at *c'c'*, and these projections are inserted in holes *m m* in opposite arms, as indicated in Figs. 1 and 2. This hinge-joint is made so as to work close, but freely, and the spring tends to throw the button ends of arms *ll* together. Their natural position is as shown in Fig. 1. Pressing *o* toward *a* will cause buttons *i i* to move outward in slots *b*, so that a pulling on either button, or both, will cause the buttons to move toward the strain.

Notch *n* in *c* is designed to facilitate the insertion of *c* in a button-hole; but I make no claim upon it.

Practical tests as to the elasticity of this device have been made, and causes that have burst the button-holes of paper collars of a given tightness have had no effect on the collars when my button was used.

Having fully described my invention, what I claim, and desire to secure by Letters Patent, is—

1. An elastic collar-fastening consisting of a slotted plate having a button for insertion in a shirt-collar band, a hook for a necktie-fastening, and supporting in the slots therein two buttons attached to spring-actuated arms, the whole combined and operating substantially as described.

2. In an elastic collar-fastening, arms *ll*,

provided with buttons *i i*, combined with slotted plate *a* and button *c*, substantially as shown.

3. In an elastic collar-fastening, arms *ll*, carrying buttons *i i*, combined with plate *a*, provided with button *c* and hook *e*.
4. In an elastic collar-fastening, plate *a*,

arms *ll*, carrying buttons *i i*, and spring A, combined substantially as described.

CARL G. HARSTROM.
